UNITED STATES PATENT OFFICE

ROBERT J. CROSSMAN, OF SAN FRANCISCO, CALIFORNIA

COMBINATION CUTTER AND GUARD

Application filed December 27, 1927. Serial No. 242,735.

My invention relates to improvements in a combination cutter and guard, and it consists in the combinations, constructions, and arrangements hereinafter described and claimed.

An object of my invention is to provide a combination cutter and guard that is designed especially for trimming the top lift of a heel so that the sides of the lifts will coincide with the sides of the heel, and in preventing the cutter from marring the surface of the heel during the cutting operation. To this end I provide a cutter having angularly-shaped teeth that tend to move the heel laterally in one direction during the cutting operation, and I provide guards for limiting the movement of the heel in this direction and also preventing the cutter from cutting beyond the planes coinciding with the heel.

A further object of my invention is to provide a device of the type described which is extremely simple in construction, and which is adjustable for adapting itself to heels of various sizes. The device may be attached to a standard machine with but slight alterations being necessary in the latter.

Other objects and advantages will appear in the following specification, and the novel features of my invention will be particularly pointed out in the appended claims.

My invention is illustrated in the accompanying drawings forming a part of this application, in which:

Figure 1 is an end elevation of the device;

Figure 2 is a top plan view of the device;

Figure 3 is a longitudinal section through the device;

Figure 4 is a longitudinal section of the housing and guard; and

Figure 5 is a perspective view of a portion of the housing and guard removed from the other parts of the device.

In carrying out my invention I make use of a support 1 that carries a shaft 2. The

shaft is rotatably mounted in a bronze bushing 3, or other suitable bearing, and is rotated by the usual belt and pulley connection, not shown. An oil duct 4 extends through the support 1 and leads to the shaft 2 for the purpose of oiling the shaft.

The parts above described are standard and form no part of my invention, except in so far as they cooperate with the parts now to be described.

On the end of the shaft 2 I mount a cutter 5 of the shape shown in Figure 3, this cutter having teeth 6 that are angular in shape and angularly disposed, as shown in Figure 5. The cutter is secured in place by a screw 7 and a washer 8. Figure 3 shows how the cutter bears against a shoulder 9 on the shaft 2.

I enclose the shaft and cutter in a housing that comprises a tubular member 10 and an enlarged portion 11. The housing has its tubular end inserted into a recess 12, and is held in this recess by friction. An opening 13 in the housing connects with the duct 4 and with an opening 15 in the bushing 3 for permitting oil to pass to the shaft 2.

The housing carries an adjustable guard that is composed of three pieces of peculiar shapes. The guard has a semi-circular portion 16 that merges into a ring 17 and this ring is received in a recessed portion 18 that extends entirely around the portion 11. The part 16 is held in adjusted position by a set screw 19 that extends through a T-shaped slot 20. The slot permits the ring 17 to be rotated slightly with respect to the part 11 for adjustment, and then the screw may be tightened for clamping the part 16 to the part 11.

The part 16 carries two guards 21 and 22. The guard 21 is semi-circular in shape and has a semi-cylindrical portion 23 resting against the ring 17. The portion 23 has slots 24 therein, through which set screws 25 extend. The slots 24 extend parallel with the

axis of the guard 21 and therefore the guard may be moved in a direction parallel with the longitudinal axis of the shaft 2. Two set screws 25 are provided and provide means for clamping the guard 21 in the desired position. The guard 21 has an inwardly extending flange 26, see Figure 4, against which the heel may be placed during the cutting operation. The heel is so placed that the top lift will bear against the guard 21. This guard may be adjusted so that the cutter 5 will only cut the top lift and will not mar the surface of the heel proper.

The other guard 22 is crescent-shaped, and is pivotally secured to the part 16 at 27, and is adjustably secured at its other end to the part 16 by a set screw 28. The set screw 28 is received in a recess 29 in the part 16, see Figure 5. The outer edge 30 of the guard 22 extends to within a slight distance of the ends of the teeth 6. The teeth project far enough to cut into the top lift.

From the foregoing description of the various parts of the device, the operation thereof may be readily understood.

The space indicated by X is adjustable, so that the width of this space will correspond to the thickness of the top lift. The top lift is secured to the heel in the usual manner and the portion of the top lift projecting beyond the sides of the heel must be trimmed down. Heretofore it has been necessary for the operator to hold the heel in position while pressing the heel against a cutter having straight teeth instead of angularly-shaped teeth. If the slightest slip of the operator should take place, the heel would be marred. Furthermore, the straight cutting teeth would turn up an edge upon the top lift, which would have to be cut away by hand.

The angularly-shaped cutters will prevent this edge from forming, but at the same time there is a tendency to move the heel laterally, due to the inclined teeth. This movement is in the direction of the tubular member 10 when the heel is placed in the space X, so that the top lift bears against the flange 26. Of course, the guard 21 will prevent movement of the heel as soon as the heel strikes the guard. The guard has been previously adjusted so that the operator can rest the heel against the guard and know that the cutter will not mar the surface of the heel.

The guard 22 is stationary and bears against the side of the heel for limiting the depth at which the cutter operates. The guard is so adjusted that the cutter will trim the top lift down flush with the side of the heel and no further.

In case the teeth 6 become slightly worn, the guard 22 may be moved inwardly for exposing the extremities of the teeth. In this way the cutter may be used until the teeth are worn approximately down to one-half their former size.

Certain operators place their work at a higher point than others, this being due to the height of the operator, and to the tendency of his arms to assume a certain position. The T-shaped slot 20 permits the two guards to be rocked with respect to the housing 10 so that the exposed portion of the cutter may be varied to the requirements of the particular operator.

The device is extremely simple in construction and provides a novel means for trimming the top lift of a heel without turning up a rough edge as is now the case, and without marring the heel proper.

Although I have shown and described one embodiment of my invention, it is to be understood that the same is susceptible of various changes and I reserve the right to employ such changes as may come within the scope of the appended claims.

I claim:

1. The combination with a cutter having angularly-shaped teeth, of a housing for said cutter, and blunt edged guards carried by said housing, said guards limiting the cutting effect of the width and depth of the cutter.

2. The combination with a cutter having angularly-shaped teeth, of a housing for said cutter, blunt edged guards carried by said housing, said guards limiting the cutting effect of the width and depth of the cutter, and means permitting adjustment of said guards with respect to each other and to the housing and for locking them in adjusted position.

3. The combination with a cutter, a housing therefor, said housing having an adjustable portion for exposing different parts of the cutter, a guard carried by said portion for limiting the cutting depth of the cutter, and a second guard carried by said adjustable portion for limiting the effective cutting width of the cutter, said part and guards being adjustable with respect to each other and being secured in adjusted position.

4. A guard for a rotary cutter of the character described comprising a ring, means for mounting the same in coaxial relation with the cutter, an extension of the ring extending over the cutter to cover a section thereof, and a ring fragment mounted on the first ring with freedom of axial adjustment and adapted to be projected over the uncovered portion of the cutter for reducing the effective length thereof.

5. A guard for a rotary cutter of the character described comprising a ring, means for mounting the same in coaxial relation with the cutter, an extension of the ring extending over the cutter to cover a section thereof, a front closure for the extension, and a guard adjustably mounted therein for limiting the cutting depth of the cutter.

6. A guard for a rotary cutter of the character described comprising a ring, means for
